Eugene F. McDonald, Jr., Chicago, Ill.

Application February 16, 1951, Serial No. 14,232

Term of patent 7 years

(Cl. D26—14)

To all whom it may concern:

Be it known that I, Eugene F. McDonald, Jr., a citizen of the United States, residing at Chicago, Illinois, in the county of Cook, have invented a new, original, and ornamental Design for a Combined Antenna and Weather Vane, of which the following is a specification, reference being made to the accompanying drawing, forming a part thereof.

The sole figure is a perspective view of a combined antenna and weather vane, showing my new design.

I claim:

The ornamental design for a combined antenna and weather vane, substantially as shown.

EUGENE F. McDONALD, JR.
